UNITED STATES PATENT OFFICE.

CHARLES D. SNYDER, OF DIXON, IOWA.

SEED-CORN HANGER.

No. 856,818.

Specification of Letters Patent.

Patented June 11, 1907

Application filed February 28, 1907. Serial No. 359,887.

To all whom it may concern:

Be it known that I, CHARLES D. SNYDER, a citizen of the United States, residing at Dixon, in the county of Scott and State of Iowa, have invented certain new and useful Improvements in Seed-Corn Hangers; and I do declare the following to be a full, clear, and exact description of the invention, such as will enable others skilled in the art to 10 which it appertains to make and use the same:

This invention relates to seed hangers, and has for its object to provide a device of this kind which can be cheaply made and will be 15 effective in use, and can be used an indefinite number of times and can be used upon different sized ears of corn.

In the accompanying drawings, Figure 1 is a broken side elevation of an ear of corn 20 showing a hanger in position therein; Fig. 2 is a perspective view of the hanger; Fig. 3 is a cross section through the lower end; Fig. 4 is a sectional view of one end of the hanger; and Fig. 5 is a side elevation of the detachable wings or barbs.

Referring more particularly to the drawings, 1 indicates the main portion or body of the hanger, one end of which is provided with a hook, 2, by means of which it may be suspended, and the other end is provided with wings or barbs, 3, which are adapted to engage with the cob of an ear of corn and thereby permit of the ear being suspended by means of the hooked end, 2.

35 The hanger may be formed from any suitable material, preferably, metal, in the form of a rod, or wire, preferably about four inches long and of about No. 12 gage, although these sizes and dimensions may be changed 40 or varied at will to adapt it for the use for which it is intended. The lower end, which I have called the "throat" end, is grooved longitudinally upon opposite sides, as shown at 4, by means of which the head 5 is detachably secured thereon.

45 The grooves, 4 are preferably semi-cylindrical in cross section so as to conform with the sides of the head, 5, which are seated therein, said head being preferably formed 50 from a piece of wire which is bent at its middle so as to form two parallel portions with their ends bent at an angle thereto to form the wings, 3. The grooves or recesses, 4, are deepened at their upper ends as shown at 6, until they substantially run into each other, 55 and the head is bent inward as shown at 7, at

the base of the wings, 3, so as to fit therein, the upper ends of the grooves 4 terminating abruptly, as shown at 8, which substantially correspond with the bend of the wings 3. 60 The head 5 is formed of flexible material, whereby it may be seated upon the lower end of the body, 1, by forcing said end in between the shoulders, 7, until the shoulders enter the seats, 6. The friction between the 65 shoulders 7 and the bottom of the seat 6 will be sufficient to hold the head upon the body, together with the ear of corn under normal condition, but they can be separated by applying sufficient force without injuring either 70 part, thereby adapting the head for use upon different ears of corn.

By constructing a hanger in this manner, it can be cheaply formed and readily applied to the ear, and all that is necessary is to insert the head or barbed end of the device into the pith at the butt end of the ear the desired distance, which will cause the ends of the wings to engage with the cob of the ear with sufficient force to prevent the ready removal of the device from the ear. The inward pressure of the cob upon the wings of the head will also hold the shoulders 7 into the seats, 6, and thereby assist in preventing the accidental removal of the head from the 85 body. However, when it is desired to remove the device, as when the corn is to be shelled, the body is forcibly withdrawn from the head and the head can be recovered or removed from the cob at any time after the 90 corn has been shelled, by breaking the cob. In this manner the head virtually becomes interchangeable, as it can be applied to any hook or body portion, and as they can be manufactured at such slight cost, if any of 95 the heads should be lost, or not removed from the cobs, the loss will be trifling and insignificant. After the head has been inserted into an ear in the above manner, the ear can be hung up by the hook 2 in any desired place for curing and safe-keeping until it is desired to use the corn for planting or other purposes.

Having described my invention, I claim:

1. In a corn hanger, a body provided with a hook at one end and with detachable barbs at the other.
2. In a corn hanger, a body provided with a hook at one end and having its opposite end shouldered, and wings detachably secured by 110 said shoulders.
3. In a corn hanger, a body provided with

a hook at one end and having its opposite end recessed longitudinally, a head in said recesses provided with laterally extending barbs.

5 4. In a corn hanger, a body provided with a hook at one end and having its opposite end recessed longitudinally, the upper ends of said recesses being deeper than the remaining portion, a head in said recesses having laterally extending barbs, and shoulders for fitting in said deeper portions of the recesses.

5. In a corn hanger, a body, one end of which is provided with a hook and the other end is grooved longitudinally upon opposite sides with the upper ends of the groove sub-

stantially meeting each other through the body, a head formed from a single piece of wire folded upon itself to form two parallel portions, and laterally extending barbs, said wires being bent toward each other at a point where said barbs are deflected from the straight portion. 20

In testimony whereof I have hereunto set my hand in presence of two subscribing witnesses.

CHARLES D. SNYDER.
